UNITED STATES PATENT OFFICE.

TIMOTHY L. CARLEY, LOUIS F. POWELL, AND HENRY H. BOGGS, OF SYRACUSE, NEW YORK; SAID BOGGS ASSIGNOR TO SAID POWELL.

SET-WORKS FOR SAW-MILLS.

SPECIFICATION forming part of Letters Patent No. 290,531, dated December 18, 1883.

Application filed February 13, 1883. (No model.)

To all whom it may concern:

Be it known that we, TIMOTHY L. CARLEY, LOUIS F. POWELL, and HENRY H. BOGGS, of Syracuse, in the county of Onondaga, in the State of New York, have invented new and useful Improvements in Saw-Mills, of which the following, taken in connection with the accompanying drawings, is a full, clear, and exact description.

This invention consists in certain novel devices connected with the log-carriage and head-block of a saw-mill for the purpose of conveniently, expeditiously, and accurately setting the log to the line of cutting and automatically determining the amount of lumber obtainable from said log, all as hereinafter more fully explained, and set forth in the claims.

In the annexed drawings, Figure 1 is a plan view of a log-carriage provided with our improvements. Fig. 2 is a side elevation of the same. Fig. 3 is a vertical transverse section taken on line $\alpha\alpha$ in Fig. 1. Fig. 4 is an enlarged end view of the head-block and the sliding standard mounted thereon. Fig. 5 is a vertical transverse section of the same, showing more fully the arrangement of the indicator in relation to the graduated scale on the base of the sliding standard. Fig. 6 illustrates the arrangement of interchangeable gages applied to the sliding standard for determining the number of boards or planks of different thicknesses obtainable from the log mounted on the head-block, and Fig. 7 is an enlarged top view of the stop which limits the movement of the mechanism by which the log is set to the cutting-line of the saw.

Similar letters of reference denote similar parts.

A represents the log-carriage, mounted on firm track-rails R R, arranged at one side of the saw, and parallel therewith, in the usual manner.

B denotes the head-block rigidly secured to the top of the carriage, and D is the standard or stake, against which the log resting on the head-block is clamped by the usual dog, E. Said standard or stake is provided with a prolonged base, D', by which it rides on the head-block B, and which is fitted on the head-block

in such manner that while firmly supporting the standard it allows the same to slide longitudinally. The base D' is provided on its under side with a rack, a, extending the length thereof.

F denotes a line-shaft arranged lengthwise of the carriage, and mounted in suitable bearings on the same, said line-shaft being provided with pinions c c, which engage with the racks a of the respective standards D.

e is a counter-shaft arranged at right angles to the line-shaft F, and mounted on a suitable support, b, secured to the carriage A. The end of the shaft e adjacent to the carriage is provided with a beveled pinion, f, which meshes into a beveled gear, g, attached to the line-shaft F.

To the outer end of the shaft e is attached a ratchet-wheel, g, and immediately back of this a lever, m, is hung or fulcrumed on the shaft e, which lever is provided with a pawl, n, adapted to engage the ratchet-wheel g.

h represents a semicircular rim arranged concentric with the shaft e, and secured stationary on the support b, close to the rear of the lever m. The rim h is provided with a concentric slot, s, through which projects a stud-pin, K, which comes in the path of the lever m and serves as a stop to the movement of said lever, said stud-pin being adapted to be moved along the slot s and shouldered against the outer side of the rim h, and provided at the opposite side of the same with a screw-threaded shank, on which is a nut, r, by means of which the stop or stud pin K can be clamped in its position. That portion of the stud-pin which lies in the slot s is angular, and on the end of said portion is fitted a washer, u, from which projects a pointer or indicator, l, which reaches to the periphery of the rim h, said periphery being provided with a graduated scale, i, for the purpose hereinafter explained.

v represents a dog connected to the foot of the rim h, or other suitable firm support, said dog being adapted to be thrown into engagement with the ratchet-wheel g and hold the same while swinging back the lever m to obtain a new hold on the ratchet-wheel for turning the same. The turning of the ratchet-

wheel *g*, fixed to the shaft *e*, as aforesaid, causes the pinion *f* to impart rotary motion to the line-shaft *F* by the medium of the gear *d*, and the rotation of the line-shaft transmits a 5 rectilineal movement to the sliding standard *D* by means of the pinion *c* engaging the rack *a* on the base of the standard. The log to be sawed, being mounted on the head-blocks and clamped on the standards, is thus carried by the aforesaid 10 movement of the standards toward the line of cutting, the distance of such movement depending on the stroke of the lever *m*, and the latter being controlled by the stop *K*. The scale on the rim *h* is so graduated that when the lever *m* is 15 arrested by the stop *K* the indicator *l* of the latter will point to the scale mark or number corresponding to the number of inches or fractions of inches in the distance moved by the sliding standard *D*; hence by setting the said 20 stop so as to bring its indicator *l* in coincidence with the number on the scale *i* corresponding to the number of inches or fractions of inches in the thickness of the lumber to be sawed, and then carrying the lever *m* from its 25 place of rest up against the stop *K*, the log will be moved outward on the head-block the necessary distance to cause the saw to cut the lumber of the desired thickness. A handle, *H*, is connected to the ratchet-wheel, by means 30 of which handle said wheel can be turned in a reverse direction after the pawl *n* and dog *v* have been thrown out of engagement therewith, said reverse motion retracting the sliding standard *D*, to admit of the adjustment or 35 replacement of the log on the head-block.

L represents a scale or board measure connected to the side of the base *D'* of the sliding standard, and *M* is a pointer or indicator attached to the head-block. The scale *L* is so 40 graduated that the zero-point thereof is in coincidence with the indicator *M* when the face of the standard or so-called "stake" *D* is in range with the cutting-line of the saw *U*, said zero-point being therefore at the rear or trailing end of the standard-base. This scale may 45 be divided either into inches and fractions of inches, and thus show the exact thickness of the stock of log left after the previous cut of the saw, or said scale may be divided into spaces 50 equal to one or more inches, including the saw-kerf, and thus show the actual number of boards or planks obtainable from the stock of log left on the head-block.

In order to obtain all of the aforesaid conven-

iences, we employ interchangeable gages in the 55 form of a bar having differently-graduated scales, as aforesaid, on two or more of its sides. Said bar is to be arranged along the side of the standard-base *D'*, and to be pivoted at its ends, or to be arranged rotary on its 60 axis, so that either of the scales may be turned toward the indicator *M*, as illustrated in Fig. 6 of the drawings.

It will be observed that by means of our automatic lumber scale or measure *L* the operator is enabled to ascertain at a glance the 65 number of boards or planks he can obtain from the log after it has been squared, and the measuring is effected simultaneously with the setting of the log and by the manipulation 70 of one and the same lever.

Having described our invention, what we claim as new, and desire to secure by Letters Patent, is—

1. The ratchet-wheel *g*, semicircular rim *h*, 75 provided with the scale *i* and slot *s*, the stop *K*, provided with the clamping-nut *r*, and the lever *m*, provided with the pawl *n*, in combination with the shaft *e*, provided with the pinion *f*, the shaft *F*, provided with gear *d* 80 and pinion *c*, the sliding standard or knee provided with the rack *a* and scale *L*, and the indicator *M*, attached to the head-block, all combined and operating conjointly, substantially in the manner specified and shown. 85

2. In combination with the sliding standard provided with the rack *a*, the shaft *F*, provided with the pinion *c* and gear *d*, the shaft *e*, provided with the pinion *f*, and with the ratchet-wheel *g*, the semicircular rim *h*, provided with the scale *i* and with the slot *s*, the stop *K*, provided with the clamping-nut *r* and indicator *l*, and the lever *m*, provided with the pawl *n*, all combined and operating substantially in the manner and for the purpose 95 shown and described.

In testimony whereof we have hereunto signed our names and affixed our seals, in the presence of two attesting witnesses, at Syracuse, in the county of Onondaga, in the State 100 of New York, this 9th day of February, 1883.

TIMOTHY L. CARLEY. [L. S.]
LOUIS F. POWELL. [L. S.]
HENRY H. BOGGS.
